UNITED STATES PATENT OFFICE.

DAVID TUFTS, OF PITTSBURGH, PENNSYLVANIA.

GUARD FOR FIREARMS.

Application filed January 15, 1924. Serial No. 636,403.

To all whom it may concern:

Be it known that I, DAVID TUFTS, a citizen of the United States, and resident of Pittsburgh, in the county of Allegheny and

5 State of Pennsylvania, have invented a new and useful Improvement in Guards for Firearms; and I do hereby declare the following to be a full, clear, and exact description thereof.

10 My invention relates to guards for firearms, and particularly to guards for safety slides such as are employed in connection with guns.

Some of the objects of my invention are to 15 provide a guard of such form that the safety slide is not likely to be accidentally displaced, and which serves as an index to the position of the slide, and to provide an improved form of attaching means to the 20 guard. Furthermore, the guard may have an adjustable connection to permit the application thereof to standard forms of firearms by means of screws such as those employed 25 for fastening the tang of the gun to the gun stock. In the modern type of double-barrel hammerless shot gun, when the breech is closed the hammers are at full-cock. The safety slide is located on the upper part of the tang, convenient to be pushed on or off 30 by the right thumb. In effect, the safety slide determines the movements of the triggers, and it therefore prevents the action of the triggers which would otherwise engage the sears and release the hammer.

35 Briefly stated, my invention comprises a yoke member that partially surrounds the safety slide and which may be secured to either the tang of the gun or the stock thereof, or formed integrally therewith. The guard is designed to prevent accidental movement of the slide to release position, and also serves as an index or fixed object whose relative position with respect to slide 40 enables the user to determine by even a casual glance whether the firing mechanism of the gun is locked or unlocked.

Some of the forms which my invention 50 may take are shown in the accompanying drawing wherein Figure 1 is a plan view of a portion of a gun to which my device has been applied; Fig. 2 is a similar view showing the safety slide moved to release, or unlocked, position; Fig. 3 is a sectional view taken on the line 3—3 of Fig. 1; Fig. 4 is a 55 detail view showing the guard, Fig. 5 is a view similar to Fig. 1, but showing a modi-

fied form of guard and fastening means therefor; Fig. 6 is a detail view of the guard of Fig. 5; and Figs 7 and 8 are plan views of still other modifications.

60 My invention is shown as applied to a gun having the barrels 1 mounted upon the usual tang 2 that is secured to the gun stock 3. A safety slide 4 is mounted for movement longitudinally of the gun and operates, as is common in safety devices of this character, to lock a tang or other portion of the firing mechanism against movement. The safety locking mechanism actuated by the slide may be any one of various types that are 65 well known in the art, and need not be described in detail. In order to prevent the slide 4 from being accidentally moved to the unlocked position shown in Fig. 2, I provide a guard 5 which may be secured to 70 the gun stock 3 by means of screws 6. The top of guard 5 may be either flush with, or a slight distance above, the surface of the slide 4, so that the slide is not likely to be accidentally moved forwardly to unlocked 75 position but may still be readily moved by the thumb of the user. The guard may be readily applied to guns of standard construction, no alteration in the form of the gun being necessary to permit its attachment 80 thereto, and is made of a metal such as brass 85 which may be bent to close-fitting engagement with the gun stock.

80 In Figs. 5 and 6 I show another form of guard 5^a for preventing accidental movement of the slide 4 to release position. This guard is provided with an elongated opening 7 through which the head of a screw 8 may pass, the screw 8 in some cases being also employed to assist in securing the tang 2 to the gun stock 3. The elongated opening 7 permits the guard 5^a to be properly adjusted with respect to the slide 4. This form of guard, as in the case of the guard 5, protects the rear edge of the slide from 90 accidental engagement with any object when in its rearmost or locking position.

90 Referring to Fig. 7, I show guide devices 10 that may be formed integrally with the gun stock 3, such devices taking the shape of 105 beads or ribs and being formed on the gun stock at the time it is manufactured. These members 10 project preferably a slight distance higher than the top surfaces of the safety slide 4, to prevent accidental movement of such slide through frictional engagement with any object.

Fig. 8 shows still another form of guard 11 that is formed in the shape of an upwardly projecting lug, or otherwise, upon the tang 2 of the gun, by drop forging or otherwise, during the manufacture of the gun.

In cases where the tang 2 is of sufficient width, the narrow portions of the guard 11 may extend forwardly along the sides of the slide 4, or devices 10 and 11 of Figs. 7 and 8 respectively may be combined on a single gun, thus securing the protection afforded by the guard 5 of Figs. 1 and 4.

From the foregoing it will be seen that I do not limit myself to the manner in which the guard is applied, nor to the form which such guard may take.

In the use of safety slides, difficulty is often experienced in determining with certainty whether or not the slide is in its locked position, owing to the absence of fixed object located sufficiently near thereto to serve as an index. My guard serves also as an index in that the relative positions of such guard and the slide indicates clearly whether such slide is in its forward unlocked

position or whether it is in its retracted, or locked, position. This is especially true of the forms shown in Figs. 1 and 7 wherein a movement of the slide to the position shown in Fig. 2, may be instantly detected. As to the devices of Figs. 5 and 8 position of the rear end of the slide with respect to the guard shows whether or not the slide is in unlocked position.

What I claim as my invention is:

1. The combination with a gun provided with a safety slide, of a guard therefor extending to the rear end of said slide, and means adjustable longitudinally of said slide for securing said guard to the gun.

2. The combination with a gun provided with a safety slide, of a separately formed wall-like member adapted to be mounted adjacent to said slide to shield the same against accidental movement, the said wall having a portion disposed alongside the slide to thereby also serve as an index for indicating the position of the slide.

In testimony whereof I, the said DAVID 50 TUFTS, have hereunto set my hand.

DAVID TUFTS.
